GREASE DISPENSING CONTAINER FOR
FILLING GREASE GUNS

Edwin P. Sundholm, Albert City, Iowa

Original application October 21, 1938, Serial No.
236,281. Divided and this application March 4,
1939, Serial No. 259,725

4 Claims. (Cl. 221—47.5)

The present invention relates to a grease-gun filling grease container and it relates more particularly to a grease container for shipping and/or storing relatively large supplies of grease and having means for facilitating the filling of grease-guns without the necessity for ladling out or otherwise removing the grease from the container by extraneous means; the grease-gun chamber of the conventional grease-gun being used directly for withdrawing the grease from the container.

The present application is a division of my co-pending application Serial No. 236,281 filed October 21, 1938, now Patent No. 2,214,779 issued September 17, 1940.

One of the difficulties long experienced in filling grease-guns with grease from original containers, such as drums or buckets, is that the lid of such grease-drum or grease-bucket must first be removed in order to get the grease, and the lid is frequently not replaced on the drum or bucket. The grease-drums or grease-buckets are used in garages, farms and places where all kinds of foreign matter, such as leaves, dirt, grit and dirty water frequently get into the drum or bucket and on top of the grease. One customary way of filling grease guns has been to submerge the end of the grease gun into the drum or bucket of grease and pull the follower piston of the grease-gun follower piston back so as to suck the grease into the grease-gun as in Patent No. 1,377,423. This has a dual effect of also carrying dirt into the grease-drum or grease-bucket and has the further effect of getting the grease gun reservoir smeared with grease on the outside.

One of the objects of the present invention is to eliminate the above noted objections providing an original grease container on which the lid may be left intact without ever disturbing the same so that no foreign matter can get into the grease and so that only fresh and clean grease can be furnished to the grease gun;—so that the grease-gun itself may not become foul or rendered inoperative by dirty and grit-contaminated greases.

Another object of the present invention is to provide a grease container, which may indeed be the original container or package in which the grease is shipped and sold, or it may be an intermediate container into which the grease is placed from the original package, and which container of my present invention is so arranged that the grease may be covered at all times so as to keep it clean, and withdrawn from time to time in relatively smaller quantities directly into the grease reservoir portion of the conventional grease-gun

without the necessity of separately handling the grease.

A further object of the present invention is to provide a grease container of the character stated from which substantially all the grease may be completely removed so that there is no waste of grease.

A further object of the present invention is to provide a grease container to which the generally cylindrical grease reservoir of the conventional grease guns may be screw-threadedly or otherwise detachably secured in a quick and easy manner, so that by withdrawing the follower piston in said grease reservoir of the conventional grease gun, said grease reservoir will be completely filled with a fresh supply of grease from the container forming the subject matter of the present invention.

With the above and other objects in view, the present invention consists of a generally upright cylindrical grease container formed of sheet-metal and capable of containing a substantial quantity of grease, as for instance, 10, 25, 50 or 100 pounds or more, and preferably having a freely floating piston-like follower plate therein adapted to rest on the top of the body of grease and to ride downwardly on the top surface of the grease, a socket on the outside of said container near the bottom thereof for receiving the intake end of the cylindrical grease reservoir of the conventional type grease gun, an aperture in the bottom of the grease container and a conduit communicating with said aperture and said socket for conveying grease from said container to the socket, and means for spacing the bottom of said container above the floor level or supporting surface upon which the container is to rest, sufficiently to clear said passageway and said socket.

The present invention may further include certain other novel features and details of construction, all of which will appear more fully from the following detailed description and accompanying drawings.

For the purpose of illustrating the invention, there is shown in the accompanying drawings one form thereof which is at present preferred, since the same has been found in practice to give satisfactory and reliable results, although it is to be understood that the various instrumentalities of which the invention consists can be variously arranged and organized and that the invention is not limited to the precise arrangement and organization of the instrumentalities as herein shown and described.

Referring to the drawings in which like reference characters indicate like parts,

Figure 1 represents a sectional view of the grease container embodying the present invention, having the grease-receiving end of a conventional grease reservoir of a grease gun disposed in the socket thereof.

Figure 2 represents a section generally on line 2-2 of Figure 1.

Figure 3 represents a section generally on line 3-3 of Figure 1.

Figure 4 represents a section similar to that shown in Figure 2 illustrating a modified form of construction embodying the present invention.

Figure 5 represents a fragmentary section on line 5-5 of Figure 4.

Figure 6 represents a fragmentary section of the attachment of the grease-gun receiving socket to the lubricant-reservoir, illustrating a further modified form of construction.

Figure 7 represents a fragmentary section on line 7-7 of Figure 4 illustrating a further alternative form of construction embodying the present invention.

Figure 8 represents a vertical section of the dispensing device embodying the present invention, showing a still further modified form of construction.

Figure 9 represents a fragmentary view of the grease-gun-receiving socket taken generally in the direction of the arrows 9-9 shown on Figure 4, showing a further modified form of construction.

Figure 10 represents a fragmentary section similar to that shown in Figure 7, illustrating another modified form of construction.

The grease container of the present invention is particularly intended for use in filling the small portable type grease-guns now generally used, that is, the type which may be carried about in the hand of the operator while in use, and more particularly, for use with the type of grease-gun (either manually actuated or pneumatically or electrically actuated) in which the generally cylindrical grease reservoir of the grease-gun has within it a follower-piston and in which said cylindrical grease reservoir is refilled from time to time by unscrewing or otherwise detaching from said cylindrical grease reservoir (containing said follower-piston), the high-pressure pump portion of the grease-gun (which is sometimes referred to as the "head" or high-pressure "head" of the grease-gun) and then submerging the thus opened end of the grease reservoir of the grease-gun into a supply of grease and manually withdrawing the follower in said reservoir by a suitable pull rod or chain so as to suck said reservoir full of grease. Grease-guns of this general type may be exemplified by the grease-guns shown in United States Patents Nos. 2,024,097; 2,124,077; 1,587,597; 1,692,423; 1,696,606; 1,619,126; 1,377,023; 1,790,914; 1,894,274 and 1,926,398.

The grease-dispensing container of the present invention includes a generally cylindrical body 5 of suitable diameter and height to provide the desired volumetric capacity, and a bottom 6 having an opening 7 preferably centrally thereof. For instance, for an effective ten pound capacity, that is, to accommodate ten or so pounds of grease, the convenient diameter is 9 inches, and a convenient height is 10 inches.

The entire container is formed of sheet metal, preferably suitable sheet steel such as is used for steel drums, and of a suitable gauge according to the size of the container.

The bottom 6 is preferably formed with a flange 8 of suitable depth to clear the lateral conduit 70

9 and socket 10 which will be described more fully hereinafter. The flange 8 is of an external diameter such as to telescope into the lower end of the cylindrical body 5 and is preferably drawn from the same sheet of metal as that of which the bottom 6 is formed, as for instance by being drawn in a die or a suitable press, or by any other suitable drawing operation. The flange 8 is then turned and crimped along with the lower peripheral edge of the cylindrical body 5, to form a crimped and overlapping bead-like seam 11, which unites the flange 8 with the corresponding lower portion of the cylindrical body 5, and which, at the same time, secures the bottom 6 permanently in place. The bottom 6 may also be held in place in a raised position by other means, as for instance by welding it in place to the side wall of the body 5 or by forming an outwardly pressed slight annular or peripheral groove in the body 5 at a suitable height at the lower extremity thereof into which the outer marginal portion of the bottom 6 may extend, to be held in place thereby. Likewise, the bottom 6 may have but a short downwardly extending flange which may be a spot welded to the side of the body 5.

The generally upright body 5 need not necessarily be cylindrical in shape or circular in horizontal cross-section, but may also be polygonal in horizontal cross-section, although the generally cylindrical form may be preferable.

The portion of the body 5 which is below the bottom 6 need not be continuous in its circumference, but may be cut out in parts to form a discontinuous lower extremity. Thus, for instance, three, four or more portions of the body 5 may be left projecting below the bottom 6 for the purpose of spacing the bottom 6 at a suitable distance above the lower extremity of the body.

A conduit 9 is secured to the under-surface of the bottom 6, in communication with the opening 7, so as to form a continuous but enclosed passageway communicating with the interior of the container through the opening 7 and extending to the flange 8 of the bottom. Openings 12 and 13 are extended through the flange 8 and through the cylindrical body 5 of the container in registration with the cross-section of the conduit 9, so as to form a passageway in continuation thereof. To the outside surface of the cylindrical body 5 of the container, the socket 10 is secured, also having a similar opening 14 in the end wall 47 thereof in registration with the openings 12 and 13 and in registration with the conduit 9. The socket 10 is provided with a generally cylindrical flange 15 which is internally screw-threaded as indicated at 16, to receive the externally screw-threaded ends 17 of the cylindrical reservoirs 18 of conventional grease guns. The end wall 47 of the socket 10 is made concave with a generally cylindrical curvature corresponding to the curvature of the cylindrical body 5 so that the socket 10 fits snugly against said body 5.

Within the cylindrical body 5 of the container of the present invention, a freely floating piston-like follower plate 19 is provided in operative relation to the interior diameter of said cylindrical body 5;—said follower preferably having an upturned flange 20 of suitable axial depth to afford some guidance to the follower 19 so as to tend to prevent angularity or "cocking." Radial reinforcing ribs 21 may be pressed into the follower 19 so as to stiffen the follower plate 19. The ribs 21 are generally radial and decrease in height from the center towards the periphery as indicated in Figure 1. Three, four or more such

radial ribs may be provided;—four being indicated in the drawing of Figure 1. Any suitable (conventional) handle may also be provided on the follower 19 for readily raising the follower out of the container if it is desired to refill the container after it has been completely exhausted.

A lid 22 fitting loosely over more or less frictionally telescoped into the top or over the top of the body 5 is also preferably provided for generally excluding dirt from within the container. The lid 22 is provided with a central raised portion 23 which is pressed in the sheet metal and a screw 24 is threaded into a hole in the raised portion 23, so that by removing or partly raising the screw 24, a vent is provided at the top through which air may enter at the top of the container as grease is withdrawn from the bottom of the container, so as always to maintain normal atmospheric pressure within the container. The upper periphery of the body 5 may also be suitably beaded or flared as indicated at 25, thereby to reinforce or stiffen the upper periphery of the container.

By raising the central portion of the lid 23, any rain or water which may tend to collect on the top of the lid is diverted from the vent opening at the top of the container so as to be excluded from the interior of the container.

If desired, the bottom conduit 9, may be formed by pressing suitable channel-shaped depression 26 out of the bottom 6 of the device but integrally therewith, and then superimposing a flat plate 27 over said depression and support welding it, fusing it, soldering it, or otherwise securing it to the bottom 6 along the marginal zone around the depression 26. In this form of construction, the flat plate 27 will contain the central opening 1 as indicated in Figures 4, 5, 7 and 8.

The socket 10 may either be of cast metal or it may be pressed sheet metal formed by the customary dieing operation. In Figures 4, 6, 7, 8 and 10, the socket is shown as being formed of sheet metal, although, as stated, these sockets may also be formed of cast metal.

Any of the sockets 10 may be turned up at an angle as indicated in Figure 10, so that the cylindrical grease reservoir 18 of the conventional grease-gun may be applied thereto more conveniently by the operator, particularly in the case where the dispensing device of the present invention may be of a large size which would normally stand on the floor, although this upturned socket may also be used on smaller units.

The socket 10 may be applied to the cylindrical body 5 by means of an annular eyelet 28 clamped around the aligned openings of the cylindrical wall 5 and of the bottom of the socket 10, as indicated more particularly in Figure 6. An inner member 29 may serve to provide a flat seat for the resilient gasket 30.

In Figure 8, a form of construction is shown in which a valve disc 31 is provided over the bottom opening 1. The shut-off disc 31 may be carried by a vertical rod 32 and may be welded thereto as indicated at 33. The rod 32 may extend freely through the opening 34 in the top 22 and through a corresponding opening 35 in the follower plate 19, and may have its bottom end 36 freely pivoted in a similar aligned opening 37 in the plate 27 or in the bottom 6 of the device. A cotter pin or spring clip 38 at the top of the rod 32 and extending either through a hole therein or being held in notches therein, serves to keep the rod in place. A transverse handle

portion 39 of the rod 32 serves to turn the shut-off disc 31. This will serve to prevent free drip-page of grease when the device is not in use. If desired also, a screw-threaded cap 40 may also be provided to be screwed into any of the sockets 10 when not in use.

In Figure 7, an alternative form of construction is shown in which a thin weak leaf spring 41 is secured beneath the opening 1 at one end thereof as at point 42, so as to act as a weak spring valve to minimize free drippage or drainage of grease when the device is not in use. The spring 42 is shown in the drawing of a comparative thickness greater than what it would normally have, but this is done merely for purposes of illustration and for the greater convenience in showing the spring in place.

In Figures 9 and 19, a semi-circular shut-off disc 43 is shown carried by and secured to a pivot pin 44 having a slotted outer end 45 for receiving a screw-driver or any thin flat object. The shut-off disc is held in place by means of the pivot pin in any one of the forms of socket shown, as for instance by being fastened to the gasket supporting member 29. By turning the disc by means of the screw-driver or any thin flat object, the disc 43 can be brought over the opening 46 in the gasket supporting member 29 so as to shut off the free flow of grease and can then again be turned away to permit the free flow.

Any of the shut-off means herein shown may be used whenever grease of a more or less fluid character is used or in climates where grease tends to become more fluid.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described the invention, what is hereby claimed as new and desired to be secured by Letters Patent is:

1. A dispensing device including an upright reservoir body, a bottom, an opening through said bottom, a lateral passageway extending from said opening to the side wall of the device and terminating in a socket carried by said wall of the device, a valve disposed within said socket, a lid at the upper end of said body, a follower within said reservoir body, a generally upright pivot member extending through said lid and said follower with its lower end pivotally connected to the bottom, and an auxiliary flow-control member carried by said pivot member in operative relation to said opening in the bottom.

2. A dispensing device including a generally upright reservoir body having a bottom, a discharge opening through said bottom, a lateral passageway extending through said discharge opening outwardly to the side of the device, a spring-tensioned valve plate beneath said discharge opening and in operative juxtaposition thereto, adapted yieldably to resist the flow of fluid through said discharge opening, and a screw-threaded receiving socket exteriorly of said side wall and carried thereby, and communicating with said lateral passageway.

3. A dispensing device including a generally cylindrical upright reservoir body having a bottom, a screw-threaded socket having a generally concave end wall, with said concave end wall

secured to the cylindrical side wall of said reservoir body and conforming generally to the curvature thereof, a passageway through said socket communicating with the interior of said reservoir body through an opening in the bottom thereof, an auxiliary flow-control member operatively disposed at said opening, a gasket-seat member within said screw-threaded socket presenting a flat annular gasket seat surface outwardly and having an inner bearing surface generally corresponding to the cylindrical inner end wall of said socket and bearing thereagainst, and an annular gasket within said socket in contiguous relation to said gasket seat member.

4. A lubricant dispensing device including a generally upright reservoir body, a bottom having an opening therethrough at a generally cen-

tral point thereof, a lateral passageway extending from said opening to the side wall of said device and terminating in a socket carried by said side wall, said socket having a friction-operated valve therein, a lid in the upper end of said body, a follower within said body, a generally upright pivot member extending through said lid with its lower end pivotally connected to said bottom adjacent to said opening, and a generally-flat sealing member eccentrically mounted upon said pivot member in juxtaposition with said bottom; said sealing member being adapted to be swung to cover or uncover said opening thereby to provide closure means auxiliary to the valve in said socket.

EDWIN P. SUNDHOLM.
